3 Claims. (Cl. 343—767)

This invention relates to slot antennas and is particularly directed to means for shortening the length of the slot without loss of radiating efficiency and, at the same time, improving the directional characteristics of the antenna.

The slot antenna of the type treated here may be mathematically analyzed by an elongated opening or "slot" in a plate of extended area and good electrical conductivity, as shown in Figure 1 of the accompanying drawing. The slot is analogous to the arms of a dipole antenna, each arm of which is one-quarter of the operating wave length. This requires the dipole or the slot to be at least one-half wave length long. By impressing the high frequency voltage on opposite sides of the slot midway between its ends, maximum impedance can be presented to the transmission line feeding the energy to be radiated. Since the high frequency current disperses into the ground plate, the mean electrical path between the points to which the energy is applied becomes reasonably long and radiation reasonably efficient. Heretofore, it has not been possible to construct the slot less than the quarter wave length on either side of the transmission line else the line becomes short-circuited and the antenna fails.

For various electrical and mechanical reasons it is desirable that slot lengths less than one-half wave length be employed. For example, the size of the ground plate containing the slot may be limited in size for mechanical reasons and the operating frequency may be low, thus making it unfeasible to use the half wave length slot. In cases where broad bands of frequencies are to be radiated or received, the quarter wave dimension of the slot must be taken for the lowest frequency of the band.

The object of this invention is to provide an improved slot antenna less than one-half wave length long yet having efficient radiating characteristics and good directability over a broad band of frequencies.

The object of this invention is attained by forming a slot in a ground plate of extended area inward from the edge of the plate a distance corresponding to about one-quarter of a wave length at the lowest operating frequency. Means is provided for energizing the slot near its open end. A housing may be placed over the slot to prevent its radiation from one plane of the slot, and means is provided for establishing a high impedance between the sides of the slot adjacent said open end and for obviating short-circuiting effects of the housing, said means comprising resonant stubs on either side of the slot within the housing to present a high impedance load to the slot so that high frequency energy may be transferred efficiently to the open end of the slot.

Other objects and features of this invention will become apparent to those skilled in the art by referring to the specific embodiments of the invention described in the following specification and shown in the accompanying drawing in which:

Figure 1 is a plan view of a conventional slot antenna of the prior art,

Figure 2 is a plan view of a slot antenna embodying this invention,

2

Figure 3 is a perspective view of one slot antenna embodying this invention,

Figures 4, 5 and 6 are top, edge, and bottom views, respectively, of one actual physical embodiment of this invention,

Figure 7 is an enlarged detail sectional taken on line 7—7 of Figure 6,

Figure 8 is a graph of the standing wave ratio of a broad band antenna of this invention, and

Figure 9 is a polar diagram of the field strength of the quarter wave antenna of this invention.

According to this invention, the ground plate 1, Figure 2, is slotted inwardly as at 2 from one edge of the ground plate, the length of the slot being about one-quarter of a wave length in extent as contrasted to the one-half wave length for slots of the prior art, such as shown in Figure 1. The transmission line 3 may be thus coupled directly to opposite sides of the slot adjacent the edge of the plate. The transmission line may comprise the two-wire line of Figure 2, or the coaxial line for Figure 3, or the special transmission line of Figures 4, 5, and 6. Further, the two sides of the line either may be attached directly to opposite sides of the slot as in Figure 2, or coupled to the space therebetween by an irradiating probe in the slot as suggested at 5 in Figure 3. It has been found that such a slot will radiate perpendicularly to either side to the ground plate 1, and that negligible radiation occurs from the end of the slot in the plane of the ground plate 1.

A conventional, cup-shaped housing cannot be placed over the slot to form a cavity and to confine radiation to one side of the ground plate because the housing would short-circuit the transmission line and reduce the impedance of the open end of the slot to zero. According to an important feature of this invention, the housing 10 is placed over the slot and is attached to the ground plate 1, but the housing is open-ended at the open end of the slot and the side panels of the housing are spaced outwardly from the side edges of the slot. Conveniently, three flanges 10a, 10b, 10c are formed on the edges of the housing and are soldered, brazed, or otherwise electrically and mechanically attached to the ground plate. Preferably, the inside length of the housing is the same as the length of the slot. Such a housing will prevent radiation from the slot toward the rear of the ground plate, but, as thus far described, will cause strong radiation from the end of the slot in the plane of the ground plate.

According to another important feature of this invention, radiation is reduced from the open end of the housing and slot without impairing the loading characteristics of the transmission line. Flat parallel flanges 11 and 12 are placed along either side of the slot and are extended into the housing a distance which is a significant fraction of a wave length. That is, the folded cavities formed by the housing and flanges are so proportioned as to produce an impedance at the slot, which impedance is matched to the transmission line impedance. Ideally, electric waves created between the edges of the slot by the transmission line will see two stubs or cavities exactly one-quarter wave length long when measured from this slot 60 toward the bottom wall of the housing, around the outer edges of the flanges 11 and 12, and hence to the short-circuited end of the stub between the flanges and housing at the back of the ground plate 1. This quarter wave dimension must, however, be compromised to minimize 65 radiation from the ends of the cavities at the open end of the housing. Extensive experimentation with the cavities of the type shown in Figure 3 shows that a good impedance match and minimum end radiation can be achieved for broad band operation when the mean electrical length of the stubs are each less than one-quarter of the longest wave of the operating band. Hence, the flanges 11 and

12 extend from the edges of the slot into the housing a distance corresponding to, or less than, one-eighth of the longest wave of the operating band.

Figures 4, 5 and 6 show the top, edge, and bottom views, respectively, of one particularly effective antenna of this invention. In this embodiment, the transmission line is printed on one side of a thin sheet 19 of a high grade insulating material. The printed transmission line comprises the printed strip 15 terminating at one end in a radiating probe 15a of measured area. To the other side of the insulating sheet is attached a thin foil 17 of extended area compared to the thickness of the insulating sheet and to the width of the printed transmission line 15. So called "microstrip" laminates are commercially obtainable, comprising a thin sheet of "Teflon"-impregnated fiberglass board clad on both sides with copper foil. In constructing the antenna of this invention, the foil on one side is coated with a photo-resist and is selectively irradiated by a strong light through a negative of the pattern of the printed circuitry desired. In this case, the negative is prepared to show the exact outline of the transmission line 15 and its probe end 15a. Then the unwanted portion of the foil is selectively removed in an etching solution. The window 16 in the ground plate 17, on the other side of the sheet, as best shown in Figure 7, is removed also by the etching technique if desired, the removed portion being at least as large as the desired slot. The window 16 may be formed entirely within the boundaries of the ground plate, as shown, or along one edge thereof. The window is formed to underlie the antenna probe 15a and is formed to the exact size and shape of the desired slot. Since the sandwich comprising the insulating sheet, ground plate, transmission line, and probe are mechanically bonded together and are incapable of relative movement, the precise position of the window slot with respect to the probe is easily established and reproducible in manufacture. It has been found desirable for good impedance matching and for efficient radiation to extend the area of the probe, as shown at 15a in Figure 4. The printed circuit board is then bolted or otherwise fastened to the metal chassis 18 in which the slot 16a has been cut. The edges of the window 16 of the printed circuit board are made to register with the edges of the slot 16a in the chassis. The metal angles 11 and 12 are soldered, brazed, or otherwise affixed along the edges of window 16a, and the housing 10 conveniently formed from sheet metal and with flanges 10a, 10b and 10c, is placed over the angles as shown and fastened to the chassis. The depth and width of the housing 10 is selected to provide the stub cavities 50 around the angles 11 and 12. The open end of the housing is placed flush with the edge of the ground plate. The details of the slot structure are exaggerated in Figure 7 to better show the arrangement of parts.

Figure 8 is a diagram of the voltage standing wave ratio of the quarter wave slot antenna of Figures 4, 5 and 6 for various frequencies, when the probe and slot has the specific dimensions shown in Figure 8. Alteration of any of the dimensions will, of course, alter different small portions of the voltage wave pattern but will not materially change the broad outline of the wave pattern. Where the dimensions of the probe end of the printed transmission line are of the specific values shown in Figure 8, it is seen that the antenna has a remarkable broad band characteristic, the response being substantially uniform from 1800 to 3600 megacycles. The H plane radiation pattern of the quarter wave slot antenna for frequencies of the order of 2000 megacycles is shown in

Figure 9, the principal lobe of the antenna pattern being outward from one side of the quarter wave slot with little radiation from the rear or open end of the housing.

Many mechanical modifications may be made in the specific structure shown without departing from the scope of the invention as defined in the appended claims.

What is claimed is:

1. A slot-type antenna comprising a ground plate, the plate having a window therethrough adjacent one edge of the plate, said window extending inward from said edge a distance approximately one-quarter of a wave length at the lowest operating frequency of the antenna, means for activating said window with energy of said operating frequency, a housing attached to one side of said plate and enclosing said window to confine radiation from the other side of said plate, said housing being open at the end adjacent said edge to prevent short-circuiting said window at said edge, and means to prevent radiation from the open end of said housing comprising flanges along the side edges of said window and extending into the cavity of said housing to form short-circuited stubs along either side of the window.
2. In a unitary slot antenna assembly, a ground plate of extended surface area, a slot in said plate, a transmission line for energizing said slot at an operating frequency, means for matching the impedance of said slot at said frequency to the impedance of said transmission line comprising a rectangular-type housing affixed to said plate along lines parallel to and spaced from the side edges of said slot, flanges along and coextensive with the side edges of said slot and extending into said housing to form folded cavities, said cavities being open at the slot end and short-circuited at the other end by said plate.
3. In combination in an antenna structure, a sheet of insulating material of good insulating properties at microwave frequencies, a strip transmission line affixed to one surface of said sheet, a ground plate of extended area against the other surface of said sheet, an elongated slot in said plate, said transmission line terminating opposite said slot, said slot being about one-quarter wave length long and being effectively open circuited at one end for the operating frequency, flanges along the side edges of said slot, and a housing attached to said ground plate and enclosing said slot and flanges, said flanges having such width and said housing being so spaced from said flanges as to form elongated impedance matching stubs along opposite edges of said slot.
